UNITED STATES PATENT OFFICE.

JOHN RAPHAEL ROGERS, OF BROOKLYN, NEW YORK, ASSIGNOR TO MERTENTHALER LINOTYPE COMPANY, A CORPORATION OF NEW YORK.

LINOTYPE-MACHINE.

No. 846,055.

Specification of Letters Patent.

Patented March 5, 1907.

Application filed October 27, 1906. Serial No. 340,838.

To all whom it may concern:

Be it known that I, JOHN RAPHAEL ROGERS, of borough of Brooklyn, county of Kings, and State of New York, have invented 5 a new and useful Improvement in Linotype-Machines, of which the following is a specification.

This invention has reference to linotype-machines of the organization represented in 10 Letters Patent of the United States, No. 436,532, and generally known under the trade-mark "Linotype," wherein the composed line of matrices, after removal from the mold, is presented to mechanism by 15 which the matrices are removed, one at a time, from the line and presented to horizontal feed-screws, by which they are moved along a distributor-bar, toothed at the lower edge to engage the teeth of the matrices and 20 hold them in suspension until they arrive over the proper magazine-channels.

The aim of the invention is to adapt the separating mechanism to handle in connection with the matrices very thin spaces, com- 25 monly known as "hair-spaces," thinner than the matrices and incapable of separation by the mechanism heretofore in use.

The separating mechanism consists, as heretofore, of parallel rails, on which the 30 matrices are sustained by their upper ears and along which they are advanced against stop-shoulders successively into the path of an underlying dog, by which the matrices are lifted one at a time clear of the detaining- 35 shoulders and into engagement with the feed-screws.

As heretofore constructed the lifting-dog is provided with a shoulder having a thickness equal to the thinnest matrix in order 40 that it might lift this matrix without affecting the next one in line. This shoulder was necessarily made of a width greater than the thickness of the hair-spaces, and therefore it 45 could not lift and release a hair-space without at the same time engaging the next matrix. To overcome this difficulty, I provide hair-spaces having their lower ends of a form different from that of the matrices, and I form the upper end of the lifting-finger not 50 only with the usual lifting-shoulder, but with special shoulders, which are adapted to engage and lift the hair-spaces, but which limit the lateral advance of the spaces in such manner as to prevent the following

matrix from being engaged and lifted at the same time.

I have shown my improvement incorporated in a separating mechanism commonly used in the Mergenthaler linotype-machine of the present day, and with the exception of the spacers and the lifting-dog, which are to be made substantially as hereinafter described, the various parts may be of any ordinary or approved construction.

In the drawings, Figure 1 is a side elevation of the distributing mechanism and the devices for delivering matrices thereto. Figs. 2, 3, and 4 are longitudinal central sections through the lifting devices of the parts in various positions which they assume at different stages of their action. Fig. 5 is a perspective view of the upper end of the lifting-finger. Fig. 6 is a view of one of the hair-spaces. Fig. 7 is a view of a matrix.

Referring to the drawings, A represents 75 the "second" elevator, so-called, movable vertically and toothed along its rear edge to sustain the line of matrices B, which are lifted from the lower part of the machine to the position shown at the top of the machine, adjacent to the distributing mechanism.

C is a horizontal pusher, by which the line of matrices is advanced endwise to the left until they are sustained by the horizontal 85 rails D resting under their upper ears. The advance of the line to the left is arrested by vertical ears d near the ends of the rails, the foremost matrix in the line bearing against these shoulders.

E is the vertically movable lifting-finger, arranged to engage under the ends of the successive matrices in order to lift them clear of the detaining-shoulders and in such position that their ears will engage the carrying-screws.

F F are the horizontal carrying-screws, by which the elevated and separated matrices are advanced in series to the left.

G is the fixed horizontal distributor-rail, 100 provided at the lower edge with longitudinal teeth permuted in arrangement to sustain the matrices until they arrive at the proper points of delivery.

The lifting-finger E is pivoted to and actuated by an angular lever H, acted upon by a cam I, which elevates the finger, and by a spring J, which effects the depression of the

finger. As the matrix-line advances to the left the finger acts under the successive matrices, lifting them clear of the rails into engagement with the screws, by which they are carried along the distributor. As each matrix is removed the matrix-line advances so that the next matrix assumes the position vacated by the preceding one.

So far as described the parts are constructed and operate in the ordinary manner.

It will be observed that the matrices are made with flat or horizontal lower ends, as shown in Figs. 1, 2, 7, &c., and that the lifting-finger E is provided at the upper end with a transverse shoulder e of a width sufficient to admit the thinnest matrix, so that when any matrix is seated thereon it will hold the finger away from the next succeeding matrix, as shown in Figs. 2 and 3, so that only one matrix can be acted upon and lifted at a time.

The hair-spaces K, one of which is shown in Fig. 6, are of the same marginal form as the matrices and provided with supporting-teeth in their upper end; but instead of being flat at the lower end they are each provided with one or more projecting lips k; so that when assembled in line with the matrices these lips will project below the latter, as shown in Figs. 1, 2, and 3. These hair-spaces are necessarily made much thinner than the thinnest matrices and of a thickness materially less than the width of the shoulder e on the lifting-finger. It is to prevent them from passing over so far on this shoulder as to permit disengagement with the next matrix that the lips k k are provided.

The finger E is provided, in addition to the usual shoulder e, with secondary shoulders e², made of such depth and so located that they will just receive the lips k. When, therefore, a line is composed of in matrices and hair-spaces the action will be as follows: The matrices will be acted upon and lifted by the finger in the usual manner, as shown in Figs. 1, 2, and 3. When, however, a hair-space arrives at the lifting-finger, its lips k will seat themselves on the shoulders e², as shown in Fig. 4. When thus engaged, the hair-space will be lifted by the finger and permitted to pass forward in the same manner as the matrices, and at the same time the hair-space will be held in such position that its right side will be flush with the right face of

the finger, so that the latter is prevented from engaging and lifting the next succeeding matrix until a hair-space has been delivered and the finger returned to its lowermost position.

The essential feature of the invention lies in giving the matrices and hair-spaces variant forms and in providing the lifting-finger with distinct surfaces to engage the matrices with hair-spaces, and it will be manifest to those skilled in the art that the hair-spaces and the finger may be variously modified without changing the mode of action or passing beyond the limits of my invention.

Having described my invention, what I claim is—

1. In a linotype-machine, the combination of matrices, coöperating hair-spaces adapted to project beyond the matrices, and a lifting-finger having distinct shoulders to lift the matrices and the hair-spaces respectively.

2. In a linotype-machine, the combination of the matrices, the hair-spaces modified in marginal form to distinguish them from the matrices, and a separating device having distinct surfaces to engage the spaces and the matrices respectively.

3. In combination with the matrices, the lifting-finger having a shoulder to lift the matrices and hair-spaces, said finger recessed to receive the projections on the hair-spaces and limit their advance over the shoulder; whereby the hair-spaces are held in position to prevent the engagement of the shoulder with the following matrix.

4. A hair-space for use in a Mergenthaler linotype-machine, having a marginal form and size corresponding to that of the ordinary matrices, but extended at the lower end to project below the matrices.

5. A hair-space for a linotype-machine, having the usual form of linotype-matrices with ears at the upper and lower ends, and with projections k, k, extending below the lower ears.

In testimony whereof I hereunto set my hand, this 23d day of October, 1906, in the presence of two attesting witnesses.

JOHN RAPHAEL ROGERS.
